UNITED STATES PATENT OFFICE.

JOHN A. BOLANDER, OF SAN FRANCISCO, CALIFORNIA.

TONE-REFLECTOR FOR MUSICAL INSTRUMENTS.

1,207,678.

Specification of Letters Patent.

Patented Dec. 5, 1916.

Application filed December 2, 1912. Serial No. 734,487.

To all whom it may concern:

Be it known that I, JOHN A. BOLANDER, a citizen of the United States, residing at No. 26 O'Farrell street, in the city and county of San Francisco, State of California, have invented certain new and useful Improvements in Tone-Reflectors for Musical Instruments, whereof the following is a specification.

10 My invention relates to the art of music, and particularly to that division of the art which treats of musical sound produced by instruments of the violin tribe. In playing such instruments, the vibrations of strings 15 are communicated through a bridge to the body of the instrument, and said body, containing a volume of confined air, is set into resonant vibrations, sound being given off into the surrounding air. The beauty and 20 efficiency of the tone is affected by the character of the environment, such as the absorptive or reflective nature of the surrounding objects; and where there is proximity of soft and yielding objects, such as draperies 25 and the face and clothes of the player, the sound is detrimentally absorbed thereby.

It is the object of my invention to provide 30 means for preventing the aforesaid detrimental effect of proximate absorbing objects on the sound of musical instruments, and particularly the effects produced on violin sound by the player's clothes; and to this end my invention consists in a reflector of 35 suitable material interposed between the instrument and the person, and shaped and arranged to receive the sound and reflect it away from the player.

It also consists, in the novel parts, combinations, and arrangements set forth in the 40 following description, particularly pointed out in the claims, and illustrated in the accompanying drawing, of which—

Figure 1 is a view in side elevation of a violin, showing my sound reflector in place; 45 Fig. 2 is a perspective view of my sound reflector; and Fig. 3 is a view partly in section, taken along the line $a-a$ Fig. 2, looking in the direction indicated by the arrows.

The same symbol of reference marks the 50 same part in whichever view said part may appear.

Describing my invention in detail, and referring to the drawing, 1 is a sound reflector, which is formed in this instance for a violin 55 A substantially as shown in the drawings, the perspective view in Fig. 2 being espe-

cially referred to. The changes of construction needed to adapt my device to other instruments are such as any person skilled in the art can readily make from the description of the violin type contained herein, they will not be detailed in this description, it being understood that I do not confine my device to use with violins alone, but claim its use with all other instruments to which it 60 may be adapted. It is arranged to set on the back end and project toward the belly of a violin by a side portion 2 conforming in shape and size to that end and adjacent parts of the instrument, and may be made of any 65 suitable material, preferably of flexible character, such as fine leather, so as to cling closely thereto, and adapt itself to slight variations in form of the usual standard size. A curved top plate 3, and a curved 70 bottom plate 4, are attached to said side portion, the top piece extending to the front end of the tail piece B, and the bottom piece extending considerably farther toward the belly of the instrument, Figs. 1 and 2 showing the constructional features referred to, 75 with the requisite clearness.

The curves of the top and bottom plates are such as to bring them close to the body of the violin along their line of juncture 80 with the side piece, and to expand toward their middle and free edges, so as to leave space between the plates and the sounding boards of the violin which increases from the back to the forward end of the sound reflector. Arranged as described, the sound 85 from the sounding boards of the instrument, are reflected forward and away from the body of the player.

The curved plates are made of any suitable material, celluloid answering the purpose especially well, as it reflects in the way desired, and is nearly transparent. The bar 90 5 assists in giving the downward curve to the plate 4; strips 6 and 7 of soft material, like leather, are fixed all around the inside edges of the plates, and lie between the plates and the body of the violin. A chin-rest not shown, such a device being well known may be placed in position directly 95 over the reflector if desired; chamois or other suitable material also not shown may be secured around the edge of the top plate, and laid over that portion of the top plate 100 on which the chin of the player would naturally rest.

Believing I have produced novel and use-

ful improvements in that class of invention and having fully described the same to sufficiently enable others skilled in the art to which the same appertains, what I claim and desire to secure by United States Letters Patent, is:—

1. In combination with the back end of a violin and the tail-piece thereof, a forwardly projecting and expanding removable sound reflector covering said back end and tail-piece.
2. In combination with a violin, a sound reflector comprising upper and lower curved plates of reflecting material, removably fitted over the back end of the violin and gradually projecting and expanding forwardly, and a flexible surrounding side member, securing said plates.
3. A sound reflector for violins, comprising an upper and lower forwardly projecting and expanding plate, and a flexible mem-

ber adapted to secure said plates around the surrounding edges of the back portion of said musical instrument.

4. A sound reflector for a musical instrument, comprising an upper and lower plate covering the back end of said instrument and forwardly projecting and expanding therefrom, said lower plate being longer than said upper plate, and a flexible side member for securing the edges of said plates together around the surrounding back edges of said musical instrument.

In testimony that I claim the foregoing I have hereto set my hand in the presence of two witnesses, this 25th day of November, 1912.

JOHN A. BOLANDER.
